UNITED STATES PATENT OFFICE.

HENRY J. SMITH, OF MINNEAPOLIS, MINNESOTA.

CHURN AND BUTTER-WORKER.

1,390,466.

Specification of Letters Patent. Patented Sept. 13, 1921.

Application filed July 26, 1920. Serial No. 398,991.

To all whom it may concern:

Be it known that I, HENRY J. SMITH, a citizen of the United States, residing at Minneapolis, in the county of Hennepin and State of Minnesota, have invented a new and useful Churn and Butter-Worker, of which the following is a specification.

This invention relates to churns of the power operated type, and more particularly to a novel form of churn including butter working means.

The primary object of the invention is to provide a churn of this character having suitable clutch mechanism whereby the butter working rolls may be moved into and out of operation at the will of the attendant, thus eliminating the necessity of stopping the churn to accomplish the working of the butter.

20 A further object of the invention is to provide means for automatically relieving the gas within the churn, the means being timed to cause the operation of a valve at predetermined intervals.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 Referring to the drawings:

Figure 1 illustrates a longitudinal sectional view through a churn constructed in accordance with the present invention.

Fig. 2 illustrates an end elevational view 40 of the same, and

Fig. 3 illustrates a transverse sectional view taken on line 3—3 of Fig. 1.

Referring to the drawings in detail, the reference character 5 designates the supporting legs of the churn, which have right angled extremities 6 by means of which the churn is supported in an upright position, the upper extremities of the supporting leg being provided with heads indicated at 7 on 45 which the churn is supported.

The churn includes the drum or body portion 8 which is provided with a partition 9 dividing the churn into a churning compartment and a gear casing 11, the partition 55 having connection with the walls of the churn to prevent foreign matter contained

in the gear casing 11 from entering the churning compartment 10.

Supported in the end walls of the churn proper, are the bearings 12 and 13, the bearing 12 adapted to accommodate the shaft 14 forming a part of the bearing 7, while the bearing 13 accommodates the shafts 15 and 16, to permit of free rotary movement of the drum or body portion 10 with relation to the supporting legs 5.

The power shaft 15, is supported in the hollow axle 16 and extends from a point in spaced relation with one end of the drum 8, to a point substantially intermediate the width of the gear casing 11, the outer extremity of the shaft 15 having connection with the power pulley 17 in a manner to permit of movement of the pulley 17 longitudinally of the shaft 15, but at the same time prevent rotary movement of the pulley 17 with relation to the power shaft 15, so that rotary movement of the pulley 17 will impart a rotary movement to the shaft 15.

A bearing member 18 has connection with one end of the shaft 16, the bearing member 18 being however housed by the bearing housing indicated at 19, the housing being provided with a curved surface to accommodate the ball bearings 20, a coiled spring indicated at 21 being provided between the spokes 22 of the pulley 17 and the flange 23 of the housing 19, to maintain the housing 19 in operative relation with the ball bearings 20.

90 This shaft 15 is also hollow to accommodate the clutch actuating rod 24, the outer end of which is provided with a hand-hold 25 to permit of operation of the clutch actuating rod, the inner extremity of the rod 24 having connection with the arm 26, that has a lower inwardly and downwardly extending portion 27 adapted to embrace one end of the elongated gear 28 which operates on the shaft 29, carried by the bracket member 30, 100 forming a part of the shaft 16.

Operating on the shaft 16 is a gear 31, the teeth of which mesh with the gear 32 operating on one extremity of the elongated gear 28, there being provided a clutch pin 33 105 adapted to contact with the notched portion 34 of the gear 32 for clutching the gear 32 to the gear 28. Associated with the gear 32 and operating on the gear 28 is a pinion 35, which pinion is also provided with a cut out 110 portion 36 to accommodate the pin 33, so that movement of the gear 28 in one direc-

tion will cause the clutch pin 33 to move into the cut out portion 36 of the pinion 35 to clutch the pinion 35 to the elongated gear 28, which movement is accomplished through 5 the medium of the clutch operating rod 24, which as before stated has indirect connection with the gear wheel 28.

Formed integral with the gear 31, is a pinion 37, which pinion 37 also meshes with the 10 pinion 35, and this pinion 37 also forms a part of the disk 38, to which are attached the laterally extending arms 39, that carry the friction disks 40 and 41 for purposes to be hereinafter more fully described.

15 As shown, the friction disk 42 is formed integral with the shaft 15, and is provided with suitable raceways to receive the ball bearings 43, which ball bearings also operate against the movable disk 44 which 20 operates on the hub 45 of the arm 46, the lower end of which arm has connection with the shaft 29.

Friction disks 47 are provided with tongues 48 adapted to be positioned in 25 grooves 49 formed in the hub 45 to prevent rotation of these disks, for braking purposes. The disks 50 which are carried by the shaft 15 are also provided with suitable grooves in shaft 15. From the foregoing 30 it is obvious that when lever 68 is released to the right, the spring 21 shoves pulley 17 out and with it shaft 15 and disk 42, compressing the group of disks 41 between disks 42 and 38 so that the friction generated causes the operation of the churn. When lever 68 is moved to the left compressing spring 21 the group of disks 41 35 separate and lose their driving power. If lever 68 is moved farther, the group of 40 disks 40 are compressed between disk 46 and disk 44 by action of the ball bearing 43 and disk 42 causing the churn and all its working parts to remain stationary while disk 42, shaft 15 and pulley 17 are 45 still free to revolve.

Rotary movement of the arm 26 is prevented by means of the pins 51, which extend laterally from arm 46, and contact with the arm 26, however the arm 26 may 50 be moved into engagement with the pins 52, carried by the pinion 53, for preventing rotation of the pinion 53.

This pinion 53 imparts rotary motion to the pinion 54 which is carried by the 55 shaft 55 mounted on the partitioning wall 9, the pinion 54 however being designed to impart rotary movement to the pinion 56 mounted on one extremity of the shaft 57, the opposite extremity of the shaft supporting the sprocket wheel 57, which transmits motion to the sprocket wheel 58 through the medium of the chain 59.

Thus it will be seen that rotary movement is imparted to the pinion 60, which in turn 60 imparts rotary motion to the pinion 61,

which pinions 60 and 61 have connection with the shafts 62 that support the butter working rolls 63, so that when the clutch actuating rod 24 is moved to a predetermined position, the butter working rolls are 70 rotated.

The pinion 64 is secured to the partitioning member 9 by means of the flange 65, the teeth 66 of the pinion 64 being in mesh with the teeth 67 of the elongated gear 28, 75 so that movement of the gear 28 will cause a relative movement of the pinion 64 with the result that the churn or body portion may be rotated.

Carried by the bracket member 30, is an 80 arm indicated at 68 which extends at right angles and is provided with a shoe 69 adapted to contact with the movable pin 70 which operates in the tubular bearing member 71, the pin 70 having its upper end however in 85 contact with the rocking arm 72 which has one end thereof contacting with the spring pressed valve member 73. From the foregoing it is obvious that upon rotation of the arm 68, the valve member 73 is rotated 90 at predetermined intervals to release gases from the compartment 10.

In operation when lever 25 is moved to the right it carries with it lever 26, and lever 26 shoves pinion along shaft 29 so that the jaws 95 33 on pinion 28 are brought into engagement with the jaws 34 on gear 32 causing the churn to revolve at the churning (or high) speed, when lever 68 is released to allow the clutch disks in 41 to become engaged. When 100 lever 25 is moved to the left (or in) gear 28 is moved out, so that jaws 33 are brought into engagement with jaws 36 on gear 35. As lever 26 moves pinion 28 into connection with the low speed (or butter working) gear 105 35, it also engages pins 52 on gear 53 causing gear 53 to be held in a stationary position so that motion is imparted to the butter working gears as they revolve around it.

If it is desired to cause the operation of 110 the butter working rolls 63, the clutch actuating rod 24 is moved forwardly to cause the arm 26 to contact with the pins 52 to prevent rotation of the pinion 53. It is therefore obvious that as the churn continues to revolve around the pinion 53, rotary movement is imparted to the butter working rolls 63 through the pinion 56, sprocket wheel 58, and pinions 60 and 61.

When the churning operation is completed 120 it is only necessary to move lever 24 in or toward the churn to throw the churn out of the high or churning speed into the low or butter working speed, and to bring the butter working rolls into action.

To facilitate the cleaning of the churn it is only necessary to remove plugs 70 and 71 and shaft 72 to enable the butter working rolls 63 to be removed from the churn.

The outer surface of rolls 63 are provided 130

with spiral corrugations which enables the movement of the rolls within the churn to be lateral, and more perfectly controlled.

I claim—

- 5 1. In a churn, supporting legs, a drum supported by the supporting legs, a partition disposed within the drum for partitioning the drum into a gear casing, an arm having connection with the partition, a gear having 30 internal teeth formed integral with the arm, means including friction disks for causing the operation of the gear and drum, butter working rolls supported within the churning compartment, a pinion having connection 35 with each of the butter working rolls, a pinion supported centrally of the partition and causing the operation of the pinions of the butter working rolls, and means for holding the pinion supported centrally of the partition member stationary, to cause the operation 40 of the butter working rolls.
2. In a churn, supporting legs, a revolving drum mounted on the legs, a partition within the drum and dividing the drum into 45 a gearing compartment and a butter working compartment, a gear having a flange for securing the gear to the partition, an operating shaft, a bracket member movable on

the shaft and carrying an elongated gear, means for moving the elongated gear into 30 and out of operation, butter working rolls within the butter working compartment, and means for automatically releasing gas from the butter working compartment.

3. In a churn, supporting legs, a revolving drum mounted on the legs, means for partitioning the drum into a gearing compartment, and a butter working compartment, gearing within the gearing compartment for rotating the drum, butter working 40 rolls within the butter working compartment, gearing for operating the butter working rolls, means for throwing the first mentioned gear into operation to cause the rotation of the drum, said means adapted to 45 throw the butter working rolls into operation, when the rotation of the drum has ceased, and means for exhausting gas from the butter working compartment.

In testimony that I claim the foregoing 50 as my own, I have hereto affixed my signature in the presence of two witnesses.

HENRY J. SMITH.
